UNITED STATES PATENT OFFICE

WILLIAM F. LOUGHMAN, OF BARRE, MASSACHUSETTS

ADVERTISING DEVICE

Application filed November 15, 1929. Serial No. 407,403.

This invention relates to a novel advertising device particularly adapted for use in displaying advertising upon windows and other transparent surfaces.

5 One object of the invention is to provide a novel device of the character specified which is adapted to be removably secured to one side of a window or other transparent surface and to display the advertising so that it is 10 visible from the other side of the window or other surface.

A further object of the invention is to provide a novel device of the character specified which may be economically manufactured 15 and readily attached to and detached from the window or other transparent surface and by which the advertising may be displayed in a manner such as to attract attention.

With these objects in view and such others 20 as may hereinafter appear, the invention consists in the advertising device hereinafter described and particularly defined in the claim at the end of this specification.

In the drawings illustrating the preferred 25 embodiment of the invention, Fig. 1 illustrates the present advertising device secured to one surface of a windowpane to display the advertising so that it is visible from without the window; Fig. 2 is a vertical sectional view 30 of the improved advertising device; Fig. 3 is a similar view showing the same applied to a window; and Figs. 4 and 5 are views in side elevation and plan respectively of a modification of the present invention.

35 Referring now to the drawings, in general the present advertising device comprises a suction cup 10 of rubber or similar composition which is concave in shape and provided with flexible marginal portions 12, 14, designed to enable the cup to be flattened against a windowpane 15 and to be held against the surface by suction. The suction cup is provided within its concave face with one or more characters 16 arranged to constitute the 40 desired advertising, and as illustrated in Fig. 1, three characters are shown comprising the wellknown trade-mark "Lux". It will be understood of course that the character or characters 16 may comprise letters, numbers, emblems, insignia, or any other device designed 45

to make up the desired advertising, and that the trade-mark "Lux" is herein shown merely for purposes of illustration.

In practice I prefer to utilize a rubber label bearing the desired characters as a means of 55 attaching the characters to the inner concave face of the suction cup and have experienced particularly good results with commercial forms of such rubber labels which are necessarily thin and may be made to adhere to the inner face of the suction cup tenaciously.

When the suction cup is applied to the surface of a windowpane such as 15, the marginal portions 12, 14 of the cup engage and grip the surface of the pane, and it has been 65 found that the presence of the characters making up the advertising, if positioned within the cup at an average minimum distance of an eighth of an inch from the extreme marginal edge of the cup, does not detract from the ability of the cup to adhere to the pane, and I therefore prefer to position the advertising characters within the cup at least such distance from the marginal edges.

70 From the description thus far it will be observed that the present advertising device affords an extremely simple and convenient method by which advertising may be displayed upon windows, upon the underside of showcases, and in various other places where 75 advertising is at present displayed only with considerable inconvenience. The device may be easily attached to and detached from the window, showcase, or other transparent member, and when once attached will remain in 80 operative position for relatively long periods of time. It is entirely unnecessary to employ adhesive or other means for attaching the present advertising device to the window or pane, thus avoiding smearing of the window, and avoiding the resulting cleaning operation. After the present device has been 85 removed from the window or pane it is not necessary to scrape any hard adhesive from the window, thus saving considerable inconvenience and expense in this respect.

90 In the modification of my invention illustrated in Figs. 4 and 5, the advertising is designed to be secured in a clip 30 attached to 95 and forming a part of a suction cup 32. The 100

clip 30 is, as herein shrown, formed by two metal members riveted or otherwise secured upon the rear face of the suction cup 32 and having portions 34, 36 designed to be capable of being sprung apart by the application of pressure under the end of the upper portion 38 to permit the insertion of a paper or other medium upon which the advertising is borne, so that when the suction cup is attached to the surface of the window or other pane, the advertising will be conveniently displayed to be visible from the exterior or other side of the window or pane. In practice it may be desirable to utilize more than one clip in connection with the attachment of any advertising of material size.

While it may be preferred to utilize the clip herein illustrated, it will be understood that other forms of fastening or holding devices may be used, and the invention contemplates the attachment of such devices to the suction cup to form a unitary structure capable of use for the described purposes.

While the preferred embodiments of the invention have been herein illustrated and described, it will be understood that the invention will be embodied in other forms within the scope of the following claim.

Having thus described the invention what is claimed is:

An advertising device of the character described comprising a suction cup designed for application to a window or other surface to be secured thereto by suction, said suction cup being provided upon its concave attaching face with a flexible rubber label, bearing advertising, affixed thereto by surface bonding and constituting a unitary part thereof whereby the label is movable in the various flexed positions of the concave cup.

In testimony whereof I have signed my name to this specification.

WILLIAM F. LOUGHMAN.
